DESIGN FOR A RANGE

Orrin Hofferbert, Beaver Dam, Wis., assignor to
Malleable Iron Range Company, Beaver Dam,
Wis., a corporation of Wisconsin

Application June 23, 1934, Serial No. 52,311

Term of patent 14 years

To all whom it may concern:

Be it known that I, ORRIN HOFFERBERT, a citizen of the United States, residing at Beaver Dam, in the county of Dodge and State of Wisconsin, have invented a new, original, and ornamental Design for Ranges, of which the following is a specification, reference being had to the accompanying drawing, forming part thereof.

Fig. 1 is a perspective view of a range with the top closed, showing my new design;

Fig. 2 is a similar view with the top open.

I claim:

The ornamental design for a range, as shown and described.

In testimony whereof I have hereunto affixed my signature.

ORRIN HOFFERBERT.
